DESIGN FOR A PACK FOR FRAGILE ARTICLES

Wallace E. Parsons and Walter H. Randall,
Waterville, Maine, assignors, by mesne assignments, to The Canal National Bank of Portland,
Portland, Maine, trustee, a national banking association

Application May 2, 1945, Serial No. 119,345

Term of patent 14 years

(Cl. D58—13)

To all whom it may concern:

Be it known that we, Wallace E. Parsons and Walter H. Randall, citizens of the United States and residents of Waterville, county of Kennebec, State of Maine, have invented a new, original, and ornamental Design for Pack for Fragile Articles, of which the following is a specification, reference being had to the accompanying drawing, forming a part thereof.

Fig. 1 is a perspective view of a pack for fragile

articles showing our new design and as seen when the pack is open, and,

Fig. 2 is a similar view as seen when the pack is closed.

We claim:

The ornamental design for a pack for fragile articles, as shown.
